UNITED STATES PATENT OFFICE.

ABRAHAM PFLANTZER, OF NEW YORK, N. Y.

SAFETY NAIL CLEANING AND FILING DEVICE.

Application filed March 19, 1924. Serial No. 700,221.

My invention relates to a safety nail cleaning and filing device, which is compact, and which can be manufactured at minimum expense.

5 My invention further relates to certain articles of manufacture, combinations, and details of construction to be more fully hereinafter described and pointed out in the claims.

10 In the accompanying drawings the same reference numerals refer to similar parts in the several figures.

Of the drawings:—

15 Fig. 1 is a perspective view of my improved safety nail, cleaning and filing device;

Fig. 2 is a vertical section through the device shown in Fig. 1;

20 Fig. 3 is a vertical section, similar to Fig. 2, with the cover open, and a finger nail of the left-hand of the user clamped in operative position, ready to be cleaned, cut and filed;

25 Fig. 4 is a detailed end elevation on the line 4—4 of Fig. 3, looking into the container with the cover thrown back, the finger of the user being omitted;

Fig. 5 is a detail plan view of the file wheel;

30 Fig. 6 is a horizontal section substantially on the line 6—6 of Fig. 2.

My safety nail cleaning and filing device includes a box or container 1, having a cover 2 pivoted at 3 so that it can swing up or out, as shown in Figs. 3 and 4. The box 1 is provided with slotted ears 4, 4 (only one being shown in Fig. 1) within which is rotatably mounted, and yet adapted to have limited lateral movement, an axle or arbor 5, upon which is mounted the file wheel 6 preferably of steel, though it may be formed of any suitable material. The yoke 7, Fig. 6, is provided with arms 8, 8 having bearings 9, 9 for the axle or arbor 5. This yoke 7 has an integral screw-threaded adjusting rod 10, the male threads of which cooperate with the female threads in the adjusting screw 11. The periphery of this adjusting screw 11 extends out slightly beyond the surfaces of the box or container 1, as shown in Figs. 1 and 6, so that by turning the adjusting screw 11 back, or forth, the yoke 7, with its arms 8, 8 will cause the entire file wheel 6 to move back or forth within the slot in the slotted ears 4, 4 of the box, thereby adjusting the file wheel 6 to or from the cleaner 12 and the clamp 13.

This cleaner 12 is preferably a spring arm secured at its end 14 by rivets 15, 15, Fig. 3, or otherwise, to the interior of the box or receptacle 1. The other end of the cleaner 12 is bent over at 16 so as to form a comparatively broad cleaning surface, which is adapted to engage with the under-surface of the nail 17 to remove foreign matter. I also preferably employ a yielding clamp 13 immediately above the cleaner 16 so as to support the nail 17 while it is being cleaned, and to take up the strain thrown on the nail by the cleaner, thereby obviating the pain and annoyance often occasioned by excessive pressure on the under surface of the nail when it is being cleaned. This clamp 13 is secured at its other end 18 by means of the rivets 19, 19, or otherwise, to the interior of the box or container 1. Preferably 70 the end of the clamp 13 is provided with a roller 20, which directly contacts with the upper surface of the nail 17, though of course this may be omitted if desired.

The periphery of the file wheel 6 is provided with a plurality of parallel grooves 21, 21, forming ridges or files 22, 22.

This file wheel 6 may be made solid, or may be provided with the spokes 23, 23. On the periphery, I provide one or more radial slots 24, 25, arranged at an angle to the longitudinal grooves and ridges 21 and 22. Within each of these grooves or slots 24 and 25 I mount a knife or blade 26, holding it in its slot in any suitable manner, such as by 90 the screws 27. The periphery or outer edge 28 of the knives 26, 26 extends slightly above the parallel groove and ridges 21 and 22, and, being arranged at an angle, they will cut or trim the very end of the nail 17. 95

My safety nail cleaning and filing device is meant primarily to be made so small that it can be readily carried in the vest pocket, or, when used by school children, it can be worn suspended from the neck by a suitable cord or chain (not shown) so that it will always be accessible to keep the nails clean; and, as it can be used by the children without danger or discomfort, due to the fact that there is no excessive pressure of the 105 cleaner 16 pressing up on the nail 17, the children will be more apt to keep their nails in good condition than they otherwise would.

It will be noted that the peripheral grooves 24, 25, two of each being preferably 110 used, are arranged at opposite angles to each other so that two of the blades 26, 26 will be

at the proper angle to cut the end of the nails 17 of the left hand; when the box or container 1 is held in the right hand, whereas the other two knives will cut the nails of 5 the right hand when the box is held in the left hand.

In using the device the cover 2 is opened and the nail 17, for example, is pressed between the cleaner 16 and the clamp 13. The 10 box 1 with its cleaner 16 is then moved back and forth at right angles to the finger 30 so as to remove any foreign matter on the under surface of the nail 17; this operation is without discomfort or pain, because the upper 15 surface of the nail is supported yielding- ily by the spring clamp 13. After the foreign matter has been removed, the adjusting screw 11 is operated to bring the periphery of the file wheel 6 to contact with 20 the end of the nail 17, if it has not already done so. Then, by moving the box 1 back and forth across the end of the nail 17, the nail will be properly filed.

In the position shown in Fig. 3 the box or 25 container 1 will be grasped in the right hand so as to operate upon the finger 30, of the left hand of the user. If the file wheel 6 is initially positioned to contact with the end 30 of the nail 17, when the nail is first inserted between the cleaner 16 and the clamp 13, the operation of cleaning the under surface 35 of the nail, will at the same time file its end.

Should the nail be too long the file wheel 6 can be turned on its pivot 5 so as to bring 35 one of the blades into the position shown in Fig. 3, which will first cut the end of the nail; then by moving the wheel 6 slightly, so as to disengage the knife 26 from the end of the nail, the longitudinal ribs 22, 22 40 can be brought into action and will file the end of the nail after it has been cut.

The operation of cleaning, cutting and filing the nails on the right hand of the user 45 is exactly the same as that just described, except that the box or container 1 will then be grasped in the left hand, and, if it is desired to cut a nail on the right hand, one of the blades 26, set at a different angle, would be employed. After the device has served 50 its purpose the cover 2 is closed and held in position in any suitable manner as by a lip 31 snapping over a small projection 32 pressed out of the box or container 1.

It is, of course, to be understood that the 55 box and cover may be made of any suitable size, of different materials, and variously engraved or otherwise decorated.

Having thus described this invention in connection with illustrative embodiments 60 thereof, to the details of which I do not desire to be limited, what is claimed as new and what is desired to secure by Letters Patent is set forth in the appended claims.

What I claim is:—

65 1. The combination in a nail cleaner of a

cleaner adapted to remove foreign matter from beneath a nail, and a clamp adapted to support the upper surface of the nail while it is being cleaned.

2. The combination in a nail cleaner of a 70 cleaner adapted to remove foreign matter from beneath a nail, and a yielding clamp adapted to support the upper surface of the nail while it is being cleaned.

3. The combination in a nail cleaner of a 75 cleaner adapted to remove foreign matter from beneath a nail, a clamp movable with respect to the cleaner to support the upper surface of the nail while being cleaned, and 80 a file to file the end of the nail.

4. The combination in a nail cleaner of a cleaner adapted to remove foreign matter from beneath a nail, a clamp movable with respect to the cleaner to support the upper 85 surface of the nail while being cleaned, and a knife to cut the nail.

5. The combination in a nail cleaner of a cleaner adapted to remove foreign matter from beneath a nail, a clamp movable with respect to the cleaner to support the upper 90 surface of the nail while being cleaned, a knife, and a file to file the end of the nail after it has been cut.

6. The combination in a nail cleaner of a cleaner member adapted to remove foreign 95 matter from beneath a nail, a clamp member to support the upper surface of the nail while being cleaned, means for resiliently pressing one of said members toward the other and means to trim the nail while being 100 held by the cleaner and clamp.

7. The combination in a nail cleaner of a cleaner adapted to remove foreign matter from beneath a nail, a clamp movable with respect to the cleaner to support the upper 105 surface of the nail while being cleaned, and means movable with respect to the nail to trim the nail while being held by the cleaner and clamp.

8. The combination in a nail cleaner of a 110 cleaner adapted to remove foreign matter from beneath a nail, a clamp movable with respect to the cleaner to support the upper surface of the nail while being cleaned, and a file movable with respect to the nail adapted to trim the nail while being held by the cleaner and clamp.

9. The combination in a nail cleaner of a cleaner adapted to remove foreign matter from beneath a nail, a clamp movable with 115 respect to the cleaner to support the upper surface of the nail while being cleaned, and a knife movable with respect to the nail and file adapted to trim the nail while being held by the cleaner and clamp.

10. The combination in a nail cleaner, of a container, a nail cleaner, a file, and means for variably positioning the file to and from the cleaner for varying the amount of the filing action.

11. The combination in a nail cleaner, of a container, a nail cleaner, a file, a knife, and means for variably positioning the file and knife to and from the cleaner for varying 5 the amount of the filing and cutting action.
12. The combination in a nail cleaner of a container, a nail cleaner, a file wheel, and means for variably positioning the file wheel to and from the cleaner for varying the 10 amount of the filing action.
13. The combination in a nail cleaner of a container, a nail cleaner yieldingly mounted in the container and adapted to remove foreign matter from beneath the nail, a yieldingly pressed clamp adapted to bear on the 15 upper surface of the nail while it is being cleaned, a file wheel, and means to adjust it to and from the cleaner and clamp.
14. The combination in a nail cleaner of a container, a nail cleaner yieldingly mounted in the container and adapted to remove foreign matter from beneath a nail, a yieldingly pressed clamp adapted to bear on the upper surface of the nail while it is being 20 cleaned, a file wheel, one or more knives mounted on the periphery of the file wheel, and means to adjust the file wheel to and from the cleaner and clamp.
15. In an article of the character described, the combination of a wheel having 25 nail filing means in its periphery, and means for supporting the nail adjacent the wheel in position for filing, and means for holding the nail in position on the supporting means.
16. In an article of the character described, the combination of a wheel having nail filing and nail cutting means in its periphery and means for supporting the nail adjacent the wheel in position for cutting 30 and filing.
17. In an article of the character described, the combination of a wheel having nail filing means in its periphery, and means 35 for supporting the nail adjacent the wheel in position for filing, said nail supporting means also serving as a nail cleaner.
18. In an article of the character described, the combination of a wheel having nail filing and nail cutting means in its periphery and means for supporting the nail 40 adjacent the wheel in position for cutting and filing, said nail supporting means also serving as a nail cleaner.
19. In an article of the character described, the combination of a wheel having nail filing means in its periphery, means for supporting the nail adjacent the wheel in position for filing and means for variably positioning the wheel relatively to said 45 support.
20. In an article of the character described, the combination of a wheel having nail filing and nail cutting means in its periphery, means for supporting the nail adjacent the wheel in position for cutting and 50 filing and means for variably positioning the wheel relatively to said support.
21. In an article of the character described, the combination of a wheel having nail filing means in its periphery, means for supporting the nail adjacent the wheel in position for filing, and a hinged casing for 55 the foregoing parts, whereby the article may be carried in the pocket.
22. In an article of the character described, the combination of a wheel having nail filing and nail cutting means in its periphery, means for supporting the nail adjacent the wheel in position for cutting and 60 filing and a hinged casing for the foregoing parts, whereby the article may be carried in the pocket.
- In testimony whereof, I have signed my name to this specification.

ABRAHAM PFLANTZER.
